(57) **CLAIM**

The ornamental design for the bird feeder as shown and described.

DESCRIPTION

FIG. 1 is a perspective view of a bird feeder showing the design;

FIG. 2 is the front elevation view thereof;

FIG. 3 is the right side elevation view thereof;

FIG. 4 is the top plan view thereof; and,

FIG. 5 is the bottom plan view thereof.

The left side elevation view is omitted because it is identical to the right side. The rear elevation view is omitted because it is identical to the front elevation view.

The broken lines shown in the drawings represent portions of the bird feeder that form no part of the claimed design.
